UNITED STATES PATENT OFFICE.

EDWARD HAMILTON, OF PHILADELPHIA, PENNSYLVANIA, ASSIGNOR TO
THE DUTCHER TEMPLE COMPANY, OF HOPEDALE, MASS.

LOOM-TEMPLE.

SPECIFICATION forming part of Letters Patent No. 228,346, dated June 1, 1880.

Application filed February 24, 1880.

To all whom it may concern:

Be it known that I, EDWARD HAMILTON, a citizen of the United States, residing in Philadelphia, Pennsylvania, have invented an Improvement in Loom-Temples, of which the following is a specification.

The object of my invention is to so secure a temple-carrier to the breast-beam of a loom that said carrier can be readily adjusted laterally to different positions on the breast-beam and securely retained in position after adjustment. This object I attain in the manner which I will now proceed to describe, reference being had to the accompanying drawings, in which—
15 Figure 1 is a plan view of part of the breast-beam of a loom with a temple-carrier secured thereto in accordance with my invention; Fig. 2, a section on the line 1 2, Fig. 1; Fig. 3, a section on the line 3 4, Fig. 1; and Fig. 4, a 20 perspective view of part of the device.

A represents part of the breast-beam of a loom, and B a temple-carrier, which consists, as usual, of a bottom plate, *a*, having a box, *b*, and ring *d*, for guiding the temple-arm *D*, the latter being acted upon by a spring in the ordinary manner.

The plate *a* has a slot, *e*, and the carrier is usually secured to the beam by means of screws, the stems of which pass through this slot and 30 into the beam—a plan which is objectionable on account of the labor involved in changing the position of the temple-carrier on the beam, and because the beam is weakened by the numerous screw-holes, and the proper retention 35 of the temple-carrier is interfered with. These objections I overcome by providing the beam with a plate, *E*, slotted for the reception of the stem of a bolt, *f*, the head of which is adapted to a recess or groove, *g*, formed in the 40 beam beneath the plate *E*, the slot of the latter being enlarged near one end of the plate, so as to permit the application and removal of the bolt.

Against the outer edge of the plate *a* of the 45 temple-carrier bears a block, *F*, which has a lug, *i*, adapted to the slot of the plate *E*, a portion of this block overhanging the plate *a*, and being slotted for the reception of the stem of the bolt *f*, which passes through the 50 slot *e* of said plate *a*, the slot *m* of the block

being bounded by ribs *n*, whereby the confining-nut *s* is elevated so far above the plate *a* as to prevent it from interfering with the spring of the temple. The lateral adjustment of the temple-carrier on the breast-beam is effected by simply loosening the nut *s*, shifting the carrier and block to the desired position, and again tightening the nut. 55

Twisting movement of the temple-carrier is effectually prevented by the block *F*, which bears firmly against the plate *a*, and, owing to the lug *i* and slotted plate *E*, can have no movement other than a direct lateral movement on the beam. In order to increase the hold of the block *F* on the temple-carrier, the 60 said block may be provided with lugs *w*, adapted to the slot *e* of the plate *a*, as shown.

If desired, the block *F* may be secured to the plate *E* by a bolt independent of the bolt *f*, which secures the temple-carrier, the arrangement shown, however, being preferred 70 on account of its economy and compactness.

I claim as my invention—

1. The combination of the slotted plate *E*, adapted to be secured to the breast-beam, the 75 temple-carrier *B*, having a slotted plate, *a*, the block *F*, forming an abutment for the plate *a*, and means, substantially as described, for securing said temple-carrier and block to the plate *E*, as specified. 80

2. The combination of the slotted plate *E*, adapted to be secured to the breast-beam, the temple-carrier *B*, having a slotted plate, *a*, the block *F*, forming an abutment for the plate, and having a lug, *i*, adapted to the slot of the plate 85 *E*, and means for securing said carrier and block to the plate *E*, as set forth.

3. The combination of the slotted plate *E*, adapted to be secured to the breast-beam, the temple-carrier *B*, having a slotted plate, *a*, the 90 block *F*, bearing against and overhanging the plate *a*, and having a lug, *i*, and slot *m*, and the securing-bolt *f* and nut *s*, as set forth.

4. The combination of the slotted plate *E*, adapted to be secured to the breast-beam, the 95 temple-carrier, having a slotted plate, *a*, the block *F*, overhanging said plate *a*, and having a slot, *m*, bounded by a rib, *n*, and the bolt *f* and nut *s*, as set forth.

5. The combination of the slotted plate *E*, 100

adapted to be secured to the breast-beam, the temple-carrier, having a slotted plate, *a*, the block *F*, having an overhanging portion, with lugs *w*, adapted to the slot, and means for securing said temple-carrier and block to the plate *E*, as set forth.

In testimony whereof I have signed my

name to this specification in the presence of two subscribing witnesses.

EDWARD HAMILTON.
